UNITED STATES PATENT OFFICE.

ELLIS A. DE GRAFF, OF DETROIT, MICHIGAN, ASSIGNOR TO LEATHER MAKERS' PROCESS COMPANY, OF DETROIT, MICHIGAN, A CORPORATION OF MICHIGAN.

TURNING TABLE FOR SKIN-DRYING PLATES.

Application filed June 18, 1923. Serial No. 646,221.

The invention relates to apparatus for the manufacture of leather and more particularly to means for facilitating the setting out of skins upon drying plates. In one process extensively used in the manufacture of leather the skins are stretched and dried by coating the same with adhesive and then pasting upon drying boards. In affixing the skins to the boards it is necessary for the workmen to use a scraping or setting-out tool by which the thick portions of the skin are stretched out and thinned while the naturally thin portions of the skin are condensed and somewhat thickened. Such operation requires that the plates should be arranged horizontally and, to reach all portions of the skin, the workman usually mounts the table on his hands and knees. The drying plates are formed of comparatively thin paper board having glazed opposite surfaces, and therefore, to avoid injury to these boards they must be supported through their entire area during the setting-out operation. Furthermore, to increase the capacity, it is desirable to utilize both sides of the board, which necessitates reversing the same on the table with care so as to avoid injury to the mounted skin.

To facilitate this setting-out operation and mounting of the skins upon opposite sides of the board I have devised a construction of turning table by which a plate, after the mounting of a skin on one face thereof, is quickly reversed and deposited on a table on which it is supported during the mounting of the second skin. The invention therefore consists in the construction of this turning table as hereinafter set forth.

In the drawings:

Figure 1 is a longitudinal section through the table;

Figure 2 is a plan view thereof;

Figure 3 is an end elevation;

Figure 4 is a view similar to Fig. 3 showing a modified construction.

My improved turning table comprises a platform A which is mounted on a suitable framework B resting upon the floor. At one edge of this platform there is mounted in bearings C a rock shaft D, which as shown is formed of a beam portion D' and stub shafts D² at opposite ends thereof. Projecting laterally from the beam portion are a series of arms E, preferably formed of T bars, which are attached to the beam at one

end and project over the platform engaging grooves F therein. The head portion of the T is substantially flush with the surface of the platform and, as its width is substantially that of the groove, an uninterrupted surface is presented for the support of the plate. G is a connecting bar between the free ends of the arms E, this being preferably in the form of an angle bar. H is a lever arm attached to one end of the shaft D, and I is a counterweight arm secured to the opposite end of said shaft. The counterweight is adjusted to balance the structure so that the rocking of the same can be easily accomplished by a movement of the lever H. J is a second platform which is arranged adjacent to the platform A on the opposite side of the rock shaft D, said platform J presenting an unbroken supporting surface for the plate.

With the construction as described the plate is first placed upon the platform A over the arms E and while thus supported the workman mounts a skin upon the upper surface thereof. As soon as this operation is completed the lever H is actuated to quickly rock the frame, thereby turning the plate and depositing it in a reversed position upon the platform J. The workman may then proceed to the mounting of a second skin upon the reverse side, after which the plate is lifted from the platform and is transported to the drying rack.

This simple construction of apparatus greatly expedites the work and also avoids injury to the mounted skin during the operation on the reverse side.

If desired, the arms E may have attached thereto a continuous plate K, as shown in Figure 4, which will provide uninterrupted support for the mounting board.

What I claim as my invention is:

1. The combination with a platform having two sections, one of said sections having grooves and each corresponding in area to a skin mounting plate, of a rock shaft extending between said sections, arms projecting from said rock shaft and engaging said grooves in one section of said platform, and means for rocking said shaft to turn the plate from the grooved section of the platform onto the other section.

2. The combination with a platform having two sections, each corresponding in area to a skin mounting plate and one section

having a grooved surface, of a rock shaft, extending laterally from said rock shaft, 15
extending between said sections, rock arms, an angle bar connecting the outer ends of
extending laterally from said rock shaft, said angle bars, one of said sections being
and of an angular cross-section, said rock provided with grooves for receiving said
5 arms engaging the grooves in one section of
the platform with the head portions of the
angle flush with the upper face of the plat-
form, and means for rocking said shaft to
turn the plate from the grooved section to
10 the other section of the platform.

3. The combination with a platform hav-
ing two sections, each corresponding in area
to a skin mounting plate, of a rock shaft
extending between said sections, angle bars
